UNITED STATES PATENT OFFICE.

MARCEL DEPREZ, OF PARIS, FRANCE.

RHEOSTAT OR RHEOTOME.

SPECIFICATION forming part of Letters Patent No. 437,412, dated September 30, 1890.

Application filed February 24, 1888. Serial No. 265,206. (No model.) Patented in France October 5, 1887, No. 186,243; in England February 7, 1888, No. 1,843, and in Belgium February 7, 1888, No. 80,562.

To all whom it may concern:

Be it known that I, MARCEL DEPREZ, electrician engineer, of Paris, in the Republic of France, have invented certain new and useful Improvements in Rheostats and Rheotomes, (for which I have obtained Letters Patent in France, dated October 5, 1887, No. 186,243; in Great Britain, dated February 7, 1888, No. 1,843, and in Belgium, dated February 7, 1888, No. 80,562,) of which the following is a specification.

In nearly all applications of electricity to industrial purposes it is usual to employ rheostats essentially composed of more or less resisting conductors in which a part of the electric energy is expended in heat. When great electric powers are employed, developed by very intense currents, the rheostats expend very notable quantities of energy, and it becomes proportionately difficult to construct them with the conducting bodies usually employed, especially metals. The problem is even more complicated if the currents employed are of high tension. Powerful high-tension currents do not bear the introduction of rheostats except with special precautions, and cannot be suddenly broken by the ordinary means. In practice metallic rheostats are always employed. These act by introducing the resistances into the current by successive fractions. With currents of high tension this process produces violent and sudden changes of potential, which cause extra currents and dangerous sparks. On the other hand, the currents cannot be broken without having first reduced them to a very weak intensity, without which extra currents and sparks, which are very prejudicial to the apparatus, are engendered. This condition with high-tension currents requires the employment of very high resistances, which never quite fulfill their object when they are obtained with the aid of metals.

Now, the rheostats which form the subject of the present invention permit of obtaining very easily as high a resistance as is desired, and of introducing it into the circuit by following a continuous variation, of maintaining it at a determined value with an absolute pressure, and of breaking the current without

a sensible spark. In order to obtain these results I employ liquids as the resisting bodies. This employment of liquid is not new in principle. It has been sometimes followed in laboratories and in experiments; but, for reasons hereinafter explained, liquids have never been employed industrially, and there is no liquid rheostat in current use. The arrangements hereinafter described have for their object to allow of this industrial use of liquids, and to thereby obtain all its advantages.

In all these arrangements there are five general characteristic and novel features, which I will first explain.

The first consists in the nature of the liquid employed. In the laboratory experiments above referred to more or less concentrated saline solutions have been used; but according to this invention I employ ordinary water. I use saline solutions only exceptionally, in cases where it is necessary to reduce the resistance—such as, for example, when rheostats are applied to currents of relatively weak tension or of great intensity.

The second characteristic feature is that, in order to be able to keep the rheostat indefinitely in the current, I provide for a continuous renewal of the liquid, so that the electrodes are immersed not in a stagnant mass but in a current of liquid. The use of ordinary water makes this method very simple, as it is simply a continuous flow. In the case of saline solutions the same liquid can be kept circulating through the rheostat (and through a refrigerator, if necessary) by a pump or other analogous apparatus.

The third characteristic feature of my improved rheostat is that the electrodes never come in contact in the liquid, so that the resistance of the rheostat is never actually reduced to zero. This I consider a great advantage, for when metallic contact is broken within a resisting fluid, and when the circuit carries a current of considerable tension, the spark occurs between the electrodes within the fluid, although such spark is never as great and destructive as if the circuit is broken suddenly outside of the resisting fluid. I have, however, provision for removing the rheostat completely from the circuit.

2
by short-circuiting the same outside of the resisting fluid by connecting the metallic conductors which lead to the rheostat. This connection takes place automatically and by the 5 continuation of the action which has reduced the resistance to its minimum value. The rheostat is then outside the circuit. Inversely, when it is desired to reintroduce it, the metallic contact is first disconnected, and 10 then the resistance of the rheostat is increased.

The fourth characteristic feature applies to rheostats which are employed as rheotomes. In this case, in order to interrupt the current 15 by one of the arrangements which are hereinafter described, provision is made for the electrodes or one of them ceasing to be in contact with the liquid. When one of the electrodes has to leave the liquid before the 20 other, it is important for this to be the one which is connected to the positive pole—that is to say, the one by which the current enters the rheostat.

The fifth characteristic feature is that the 25 electrodes which conduct the current to the rheostat and lead it away therefrom are not necessarily formed of metals or materials which are not attacked under the action of the current, such as carbon or platinum, for 30 example, which are expensive and fragile. I use, on the contrary, ordinary cheap metals, such as iron or lead. Their waste or wear in the apparatus is very slow, and the renewal by like electrodes is inexpensive.

35 Having set out the general characteristic features of novelty, I will now proceed to describe the arrangements for carrying them into effect with reference to the accompanying drawings, in which I have shown several 40 forms of apparatus embodying my invention. They are divided into three classes, viz: First, arrangements in which the electrodes are movable; second, arrangements in which the electrodes are fixed and the liquid is movable, 45 and, third, arrangements in which neither the electrodes nor liquid is movable.

Figure 1 represents a vertical section of a rheostat in which one electrode is movable. Fig. 2 is a like view of a rheostat in which 50 both electrodes are movable. Figs. 3, 4, 5, 6, 7, and 7bis are also vertical sections of rheostats in which the high-resistance fluid is movable, while the electrodes are practically stationary. Fig. 8 is a similar view of an apparatus in which an insulating partition between the electrodes is movable within the fluid. Figs. 9 and 10 are longitudinal and cross-sections, respectively, of an apparatus in which either the containing-vessel or the 55 electrodes are movable; and Fig. 11 is a vertical section of a liquid rheostat in which one of the electrodes is in the form of a pendulum movable within the resisting fluid; and Fig. 60 12 is a cross-section of the pendulum portion of such rheostat with its containing-vessel.

65 The most simple arrangement in which the electrodes are movable is shown in Fig. 1, and

consists in placing in a vessel *a*, through which a current of liquid flows, two, or preferably three, electrodes *F F' F'*, the two outer 70 *F F* being connected to one pole and the inner *F'* to the other pole. It suffices to raise the electrodes *F* in order to gradually increase the resistance and to withdraw it from the liquid to break the current without producing 75 extra current even by moving the electrode rapidly. Both electrodes may be movable and rise from the liquid together. (See Fig. 2.) Instead of a narrow vessel which only allows of a vertical movement, I can employ a 80 long vessel or trough which allows of the electrodes being moved away from each other before withdrawing one of them in order to break the current. The variation of the resistance is thus more regular. A complete 85 apparatus for effecting this is described farther on. The plates forming the electrodes have flanges at their lower ends. These flanges retain for an instant a film of liquid when the plates are raised from the body of 90 the liquid, whereby the resistance of the circuit is enormously increased at that point before the circuit is entirely broken, and thereby entirely prevent the formation of arcs and sparks when the current is broken. This provision is useful, but is not considered necessary.

In the arrangements above described, in which the electrodes are movable in the liquid, when the electrodes are rising the whole body 100 of liquid continues to conduct the current, the resistance being increased only by the diminution of the submerged surface of the electrodes; but when, on the other hand, the body of liquid diminishes at the same time as 105 the submerged surface of the electrodes the resistance increases with greater regularity.

Fig. 3 represents an arrangement in which the body of liquid diminishes. The electrodes *F* and *F'* are fixed in an insulating-vessel *a*. The liquid enters the vessel by an orifice *A* and leaves by the orifice *B* of a vertical tube 110 made of non-conducting material. This tube can be moved endwise in a gland or stuffing-box *C*, and the height of its upper end determines 115 the level of liquid between the electrodes, and consequently the resistance.

Fig. 4 represents another arrangement in which, by means of a bell or inverted vessel *b* of insulating material descending around 120 an electrode *F*, the liquid-level can be lowered. For more security this bell can be double, so as to surround both the electrodes *F F'*, as seen in Fig. 5. The liquid can be moved without moving the bell or inverted vessel either by blowing into the bell *b*, in which the electrodes are, (see Fig. 6,) or by forcing it by a pressure of air from a closed reservoir *a*, Fig. 7, into a vessel *b'*, in which the electrodes are, or by a simple plunger *f*, Fig. 7bis, of insulating material, the lowering of which raises the liquid-level, and the raising of which allows the level to go down and thereby breaks the current.

When neither the electrodes nor the liquid are made to move, the variation of the resistance can be effected by introducing an insulating-partition *d* between the electrodes. (See Fig. 8.) This mode can be very efficiently carried out by the arrangement shown in Figs. 9 and 10, in which the rheostat is in the form of a flat cylindrical vessel capable of turning upon a horizontal axis *o o'*. The vessel is partly divided by a vertical semicircular partition *C*, parallel to the ends. The electrodes *F F'* are likewise semicircular and are fixed. They are submerged in the liquid, the level of which is at *N* and the renewal of which is effected by connections at the center of the vessel. By turning the vessel the insulating-partition can be completely disengaged from or more or less engaged between the electrodes or interposed entirely between them, thus causing the resistance to vary from the minimum to the maximum by a simple and rapid operation. With this arrangement the vessel can inversely be fixed, the insulating-partition *C* being dispensed with and the electrodes being movable around the axis. They could then be more or less submerged in the liquid or be entirely withdrawn from it. The variation of the resistance would, however, be less regular than with the other arrangement.

The arrangement which I will now proceed to describe, and which is represented in Figs. 11 and 12, is a very practical form of apparatus of the class in which the electrodes or one of them are movable. The liquid is contained in a vessel or trough *V* of insulating material. It enters by an orifice *A* and leaves by an orifice *B*. Its level is determined by a partition *H*, the height of which can be varied, if necessary. The electrodes *F F'* are each formed of parallel metallic plates connected together. The electrode *F* is fixed and receives the current from a binding-screw *a*. The electrode *F'* is movable and suspended from an axis *o*. The plates of this electrode are parallel with those of the other, and can enter between them, as is indicated in Fig. 12, but without touching them. The bottom of the vessel is curved, the curve being struck from the axis from which the movable electrode is suspended. The current reaches this electrode through this axis.

The rod which supports the movable electrode is connected to a lever *G*, and a counter-weight tends to keep the rheostat open, so as to avoid accidents if the rheostat should by mistake be left to itself. According to the position given to the lever *G* the movable electrode *F'* will either be near the electrode *F*, and the resistance will then be very small or moved away from this electrode, the resistance being proportionately greater, or if the electrode *F'* be moved quite out of the water the current will be broken. On the axis of the lever is a finger *C* connected by a rod *D* of insulating material to a handle *m* adjoining the lever-handle *M*. When the movable electrode *F'* reaches the bottom of the vessel and the lever-handle *M* is let go, the finger *C* touches a block *E* and makes a metallic contact, putting the rheostat out of circuit inversely. If the rheostat is to be used, the two handles are grasped together, and consequently the finger *C* is raised and the rheostat is automatically put into the circuit.

What I claim, and desire to secure by Letters Patent, is—

1. In a rheostat or rheotome in which a liquid forms the resisting body, the combination, with the vessel for containing said liquid and with the electrodes, of an inlet for said liquid and an outlet for the same, whereby a continuous flow and consequent renewal of the liquid is maintained, as set forth.
2. In a liquid rheostat or rheotome, electrodes formed with flanges at their lower ends, whereby when said electrodes cease to be submerged in the liquid a film is momentarily retained by said flanges, as set forth.
3. In a liquid rheostat or rheotome, the combination, with a vessel *V*, having an inlet *A* and outlet *B* and with the electrodes *F* and *F'*, of the rod *P*, lever *G*, contact-finger *C*, contact-block *E*, rod *D*, and handles *M* and *m*, as described and shown, for the purpose set forth.

In testimony whereof I have signed my name to this specification in the presence of two subscribing witnesses.

MARCEL DEPREZ.
